UNITED STATES PATENT OFFICE.

ELLA R. SELL, OF SPOKANE, WASHINGTON.

COMBINED CURTAIN-POLE AND WINDOW-SHADE BRACKET.

1,347,126.

Specification of Letters Patent.

Patented July 20, 1920.

Application filed November 10, 1919. Serial No. 336,823.

To all whom it may concern:

Be it known that I, ELLA R. SELL, a citizen of the United States, residing at Spokane, in the county of Spokane, State of Washington, have invented certain new and useful Improvements in Combined Curtain-Pole and Window-Shade Brackets; and I do hereby declare the following to be a full, clear, and exact description of the invention, such as will enable others skilled in the art to which it appertains to make and use the same.

This invention relates to curtain pole and window shade brackets.

The principal object of the invention is to provide a pair of brackets one of which is provided with a spring actuated horizontally swinging extension adapted to facilitate the attaching or detaching of the curtain pole.

Another object of this invention is to provide a bracket of the character described which is simple in construction, and is cheap to manufacture.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction within the scope of the claims, may be resorted to without departing from the spirit or sacrificing any of the advantages of the invention.

In the drawings:

Figure 1 is a perspective view showing the application of my invention.

Fig. 2 is a top plan view.

Fig. 3 is an enlarged side elevation of a bracket constructed in accordance with this invention.

Fig. 4 is a plan view of the blank from which the body of the bracket is formed.

Fig. 5 is a plan view of the blank from which the extension is formed.

Fig. 6 is a detail sectional view through one end of a curtain pole.

Fig. 7 is an end view thereof, and

Fig. 8 is a side elevation of the bracket showing a modification.

Like reference numerals designate corresponding parts in all the figures of the drawings.

Referring to the drawings, 5 designates a window casing to which a pair of brackets 6-6 are attached.

Each bracket is formed from sheet metal and comprises a body A and a horizontally swinging extension B. The body A is transversely folded upon the dotted line 7 to form an attaching plate 8. The forward end of the body is formed with a pair of spaced ears 10-10 which are bent to form alined 65 knuckles. The body is centrally formed with a longitudinal and outwardly pressed groove 11, the inner end 12 being disposed in spaced relation to the attaching plate 8 and the outer end 13 merging with the forward end of said body portion. The end 13 is cut-away, as at 14, for a purpose herein-after described.

The extension B comprises a head 15 having a neck 16, said neck being formed with 75 a longitudinal and outwardly pressed groove 17, the inner end 18 thereof being disposed in spaced relation to a concentric opening 19 formed in the head 15. The outer end of the groove 17 is cut-away, as at 20, for a purpose hereinafter described. Formed in the neck 16 on either side of the groove 17 is a pair of spaced ears 21-21 which are respectively bent to form knuckles, the knuckles of the extension alining with the 85 knuckles of the body. A pivot pin 22 is disposed within said alined knuckles for permitting the extension B to swing horizontally. It will be observed in this connection that the cut-away portions 14 and 90 20 of the grooves 11 and 17 permit of the extension B to swing outwardly. Disposed within the alined grooves 11 and 17 is a coil spring 23, the ends thereof being secured by rivets 24-24. By means of this spring, 95 the extension B is yieldingly held in alinement with the body A, but permitting of said extension to swing outwardly when so desired.

Formed in the body portion A of one of 100 the brackets is an angular slot 25 adapted to receive one end of a shade roller 26, as will be readily understood, the other end of said roller fitting in a circular bearing 27 formed in the body A of the other bracket, 105 as will be readily understood.

A curtain pole 28 is provided at each end with a circular cap plate 29, said plate being secured by nails 30 or other suitable fastening means. This plate is centrally 110

formed with an opening 31 wherethrough is driven a bearing pin 32, said pin being centrally formed with a flange 33 for limiting the inward movement of said pin.

5 In practice, when it is desired to attach the pole 28, the extension B of either bracket is swung outwardly against the tension of its respective spring 23. The pins 32 of the roller are then respectively engaged 10 within the openings 19 of said extensions, and immediately upon the release of said extensions by the operator, these springs 23 will cause the same to immediately return to their normal positions and thereby support the pole.

15 In the modification, as illustrated in Fig. 8 of the drawings, the body A of each bracket is provided on its exterior face with an ornamental knob 34, said knob being of any suitable design. This knob is secured 20 to a respective body B by rivets, solder or any other suitable fastening means.

What is claimed is:

1. In a bracket for the purpose described, 25 a body portion, an extension connected thereto for swinging movements, and a yieldable means connecting the body por-

tion and the extension for normally holding the latter in alinement with the former.

2. In a bracket for the purpose described, 30 a body portion, an extension connected thereto for swinging movements, said body portion and extension being respectively formed with aligned longitudinal grooves which merge one with the other, and a coil 35 spring disposed within said grooves and connected at its ends to the body portion and to the extension for normally holding the latter in alinement with the former.

3. In a curtain pole support, the combination with a pair of brackets, each bracket including a body portion and an extension connected thereto for outwardly swinging movements, and a yieldable means connecting the body portion and the extension of 40 each bracket for normally holding said extension against outward movement.

In testimony whereof I affix my signature in presence of two witnesses.

ELLA R. SELL.
